UNITED STATES PATENT OFFICE

JOHN W. O'DONNELL, OF SALEM, MASSACHUSETTS, ASSIGNOR TO THE TURNER TANNING MACHINERY COMPANY, OF PEABODY, MASSACHUSETTS, A CORPORATION OF MAINE

MACHINE FOR WORKING LEATHER AND OTHER SHEET MATERIAL

Application filed April 10, 1924, Serial No. 705,716. Renewed January 3, 1929.

This invention relates to machines for treating sheet material. The illustrated embodiment of the invention is especially designed for performing operations such as 5 setting operations on heavy leather and particularly for setting and rolling leather known to the trade as backs, butts, bends, sides and shoulder pieces. It will be understood, however, that various important features 10 of the invention may have other applications and uses as in unhairing, finehairing, scudding, fleshing, and putting out operations, as well as in different treatments of other sheet material.

15 It is an object of this invention to provide an improved machine which may be so controlled that a given piece of work or any portion thereof may readily be repeatedly operated upon once it has been introduced 20 into the machine, thereby obviating the necessity of repeated handling of the work and enabling the operator to treat a given piece of work in accordance with the characteristics of the work and the results that it is desired 25 to attain. It is a further object of the invention to provide a plurality of operating parts for simultaneous operation on the work so arranged as to be particularly effective in 30 operation while at the same time assisting in the feeding of the work in opposite directions 35 during repetition of the treating operations upon the whole or upon any given portion of the work.

With these ends in view, and in accordance 35 with important features of the invention, the illustrated machine comprises a pair of work operating cylinders spaced with respect to each other and arranged to co-operate simultaneously with a bed roll which serves also 40 as a feeding means in co-operation with a feed roll, the cylinders being driven in opposite directions and preferably at a higher rate of speed than the work feeding means. In order that the whole piece of work or any 45 portion thereof may be operated upon as often as the conditions may require, means is provided under the control of the operator for reversing the direction of rotation of the feed rolls at any time while the cylinders continue to rotate in the same directions as be-

fore. By this arrangement one of the cylinders aids the feed rolls in feeding the work in one direction and the other cylinder operates as a feeding means while the work is being fed in the reverse direction. With the cylinders turning in opposite directions and at a higher speed than the feed rolls, both cylinders are particularly effective in their operations on the work and both cylinders operate during the direct feed of the work 55 and also during the reverse feed while at the same time serving alternately to assist in the feeding operations.

Since the illustrated machine is particularly adapted for setting the grain of heavy leather it is desirable to provide also for heavy rolling of the leather simultaneously with the setting operations. This is effected in the illustrated machine, wherein the bed roll is movable from work receiving to work clamping position, by providing the bed roll with an unyielding support in the plane defined by the parallel axes of the feed roll and bed roll. Hence, the work may be clamped firmly between the bed roll and feed 60 roll through the operation of heavy springs which press upon the feed roll causing the latter to clamp the leather upon the unyielding bed roll and to exercise heavy rolling 65 pressure during the feeding operations.

In the construction shown the feed roll may be adjusted so as to approach more or less closely to the bed roll without touching the same, whereby danger of damage to the bed roll by the feed roll is obviated. Preferably 70 and as shown adjustment of the spring means backing the feed roll is provided for to pre-determine the pressure of the rolling operations while permitting adjustment of the feeding means to the inequalities of the work. Conveniently the working cylinders are so mounted that the degree of pressure exerted by the cylinders upon the work during operations thereon may be predetermined by adjustment to obtain the desired results in accordance with the judgment of the operator. In the illustrated machine, the bed roll and 75 one of the cylinders are so mounted as to swing away from each other into a wide open work receiving position, power means being 80

provided for returning the movable cylinder and the bed roll to operative position in which the work is clamped firmly between the bed roll and the feed roll preliminarily to the 5 rolling and setting operations on the work.

10 The setting and rolling operations on a given piece of work to secure uniformity of results are facilitated by the control which the operator possesses with respect to the machine, enabling him to treat any given part of the work repeatedly and then to pass the entire piece of work continuously past the cylinders thereby insuring that no lines of demarcation will appear on the finished 15 work and that the grain side will be left with a clear even color.

10 It will be understood that various important features of the invention are not restricted in their applications to machines of the double-cylinder type but that they may have other applications and uses as, for instance, in single cylinder machines employed in treating hides and skins.

These and other features of the invention 25 and novel combinations of parts will be described in the specification and pointed out in the appended claims.

In the drawings,

30 Fig. 1 is a front elevation of the machine illustrating one embodiment of the invention, the machine being in open, work receiving position;

Fig. 2 is a detail view of the gear driving mechanism;

35 Fig. 3 is a vertical transverse section of the machine disclosing the parts for supporting and operating upon the work, the parts being in work receiving position;

40 Fig. 4 is a view similar to Fig. 3 showing the parts in position to operate upon the work;

Fig. 5 is an end view of the machine looking from the left in Fig. 1;

45 Fig. 6 is a detail illustrating the yielding mountings for the feed roll and for one of the cylinders;

50 Fig. 7 is a detail in plan view from above illustrating the connections from the treadle to the parts which control the opening of the machine into work receiving position and the closing into work operating position;

Fig. 8 is an end view, partly in section, showing the parts in Fig. 7 from another viewpoint;

55 Fig. 9 is a plan view from above of the connections between the manually controllable lever and the parts which may be operated to reverse the direction of feed of the work at the will of the operator;

60 Fig. 10 is an end view partly in section showing the mechanism of Fig. 9 looking from the right in Fig. 1; and

Fig. 11 is a top plan view of the machine shown in Fig. 1.

65 In the illustrated machine the means for

feeding the work comprises a bed roll 20 mounted in bearings at the upper ends of two swing arms 22 each mounted fixedly at its lower end upon a shaft 24, the arrangement being such that the swing arms are secured to the shaft 24 at points closely adjacent to the heavy solid bearings for the shaft in the frame of the machine, one of the bearings being shown at 26 (Fig. 5). For co-operation with the bed roll 20 there is provided a feed roll 28 mounted in bearings 30 supported for adjustment in a vertical direction in guideways 32 at each end of the feed roll, adjustment being secured by proper manipulation of heavy screw threaded bolts 34 (Fig. 5). It will be understood that the bolts 34 in connection with the bearing blocks 30 permit adjustment of the feed roll 28 toward and from the bed roll 20 and that they serve an additional purpose in limiting the movement of the feed roll toward the bed roll so that the former cannot contact with the latter to cause damage thereto. In order that the feed roll may clamp the work upon the bed roll with a yielding pressure there is provided a heavy spring 36 in connection with each bearing block 30 interposed between the upper surface of the block and an adjustable member (Figs. 4 and 6) at the upper end of the guideway 32. Upon rotation of a screw threaded member 40 the member 38 is caused to rise or to descend to adjust to a predetermined extent the pressure of the spring 36 with respect to the feed roll 28 and the work to be operated upon, in accordance with the judgment of the operator. It will be observed that the bed roll 20 when in operative position beneath the feed roll 28 has its axis positioned in the plane defined by the axes of the roll 28 and the shaft 24 and hence that the bed roll 20 is so supported as to serve as an unyielding support for the work. Hence, a suitably heavy rolling operation on the work may be obtained by proper adjustment of the feed roll 28. At the same time the feed roll will yield and thus adjust itself to inequalities in the work.

The means for performing other operations on the work in the illustrated machine comprises a pair of cylinders 42, 44 provided with spirally arranged blades 46 extending in opposite directions from the longitudinal center of the cylinder, as most clearly shown in Fig. 11 of the drawings. Preferably, both cylinders 42 and 44 are each provided with blades or vanes of different spirals so that if the blades 43 of one spiral do not lay the grain of the work in a proper manner the other blades 45 of a different spiral will do so. In the construction shown the rear cylinder 42 is mounted in the frame of the machine by means of bearing blocks at each end of the cylinder one of which is shown at 48 (Fig. 6), the blocks being adjustable each in a guideway 50 in the frame of the ma-

chine. For adjusting each block to secure the desired relation to the bed roll there is provided a heavy threaded bolt 52 for engagement with the lower end of the block 48, said bolt being adjustable in the frame in a well-known manner, as indicated in Fig. 6 of the drawings. As shown, a heavy spring 54 is utilized for pressing the bearing block 48 in a direction to hold the cylinder 42 yieldingly against the work interposed between it and the bed roll 20, the arrangement of the spring 54 and the adjusting means therefore being similar to that of spring 36 already described in connection with the feed roll bearing blocks 30. By means which will be hereinafter described, the bed roll 20 is brought into a definite position with relation to the feed roll 28 and the rear cylinder 42 and held in that position during the operation of the machine. Hence, the force with which the bladed cylinder 42 presses upon the work is predetermined by adjustment of the screw threaded bolt 52 and the tension of the spring 54. After the bed roll 20 is moved into work operating position, as shown in Fig. 4, the front cylinder 44 is brought into its final co-operative relation with respect to the bed roll. After the work has been operated upon to the desired degree the bed roll and the front cylinder 44 are caused to move to their initial positions illustrated in Fig. 3 of the drawings. It is in this position of the parts that the work is introduced by throwing it over the bed roll 20. In order that the cylinder 44 may move toward and from the bed roll in the manner already described, it is mounted at its ends in two oscillatable arms 60 each pivoted loosely on a shaft 62 on the frame of the machine. At its free end each arm 60 is connected by a link 64 pivoted to the arm and having a screw threaded portion 66 arranged to pass loosely through a block 68 pivoted between a pair of bell cranks 70, 72 (Fig. 1), fixedly secured at their lower ends to a stub shaft 74 mounted for rotation in bearings secured to the base portion 76 of the frame of the machine. On the end of the screw threaded member 66 which projects beyond the block 68 is a spring 78 (Fig. 4) located between a collar 80 adapted to be adjusted to tension the spring 78 and to afford a backing for the spring so that the latter presses against a second collar 82 which is in contact with block 68, the arrangement being such that the member made up of link 64 and the screw threaded rod 66 may move relatively to the block 68, thus permitting the swing arms 60 to approach or recede from the bed roll 20 in accordance with inequalities in the thickness in the work interposed between the cylinder 44 and the bed roll 20. In other words, the springs 78 permit the bladed cylinder 44 to adjust itself to variations in the thickness of the work, the bladed cylinder 44

being mounted unyieldingly in the swing arms 60.

The illustrated means for moving the bed roll 20 and the movable cylinder 44 to operative position and also in the reverse direction to work receiving position is best shown in Figs. 1, 3 and 4. The said means comprises a shaft 86 extending along the rear of the machine in parallel relation to the feed rolls and the cylinders, the shaft having its ends mounted in upright portions of the frame of the machine. Mounted upon the shaft 86 at each end thereof is an eccentric 88 surrounding which is an eccentric strap 90 having fixedly connected thereto a projection 92 to which is adjustably connected a turn buckle 94 having threaded connections with a link 96 pivoted at its other end, as at 98, (Fig. 3) near the upper end of one of the arms 22. It will be readily understood that upon rotation of the shaft 86 through 180° the bed roll 20 will be moved from work receiving position to work clamping relation to the feed roll 28 or in a reverse direction. Mounted upon each end of the same shaft 86 is a second eccentric 100 having an eccentric strap 102 surrounding it to connect the eccentric through a link 104 to the bell cranks 70, 72, the link 104 being extensible and having its end pivoted to a block 106 adjustably mounted in a guide member 108 rigid with the upper end of the bell crank 72. It will be observed that the eccentrics 88, 100 are so mounted upon the shaft 86 that they counterbalance each other so that there is no strain on the shaft and so that, during the rotation of the shaft in a counter-clockwise direction in Figs. 3 and 4, the movable cylinder 44 is raised in a direction away from the bed roll 20 upwardly out of the path of the bed roll so that the latter may be swung to the position shown in Fig. 3 where it is accessible for receiving the work. It will be observed further that as the front cylinder moves upwardly the bed roll moves downwardly so that they counterbalance each other thereby lessening the strain and jar on the machine. The next half rotation of the shaft 86 in the same direction serves to bring the bed roll 20 into operative relation to the feed roll 28, as shown in Fig. 4, the bed roll being closely followed into operative position by the movable cylinder 44. Through the adjustable link 104 and the adjustable block 106 the throw of the bladed cylinder 44 may be accurately determined. And, as a further means of adjustment, the connection between the link 64 and the bell cranks 70, 72 is also adjustable through a turn buckle 110 on the screw threaded member 66. This adjustment is especially serviceable in adjusting the movable cylinder to the bed roll as the latter wears in use. By the adjusting means just referred to the movable cylinder 44 may have its path of movement accurately predetermined so

that it will occupy the exact desired position with respect to the bed roll 20. It may thus be brought into very close juxtaposition to the bed roll so that any work interposed between the bed roll and the cylinder will receive the pressure of the cylinder, the pressure being adjustably predetermined through the proper tensioning of the spring 78, as before described.

10 **Means is provided for driving the bladed cylinders positively and in opposite directions, the said means comprising in the illustrated construction a gear 120 (Fig. 5) secured fixedly to the shaft or journal 122 of 15 the bladed cylinder 42, the said gear 120 being arranged to be constantly in mesh with a gear 124 revolving loosely on a stub shaft 62 mounted in a bearing in the frame of the machine and in a bearing 128 carried by a 20 bracket 130. Fixedly secured to the hub of the gear 124 is a chain sprocket 132 around which passes a chain 134 operative to connect the sprocket 132 with a second sprocket 136 fixedly secured to the shaft or journal 138 of 25 the movable cylinder 44. Since the cylinder 42 is positively driven by means which will be hereinafter described, the movable cylinder 44 is also positively driven through the chain and other connections just described, it being 30 obvious also that the direction of drive of the cylinder 44 will be the reverse of the direction of drive of the cylinder 42. Since the oscillatable arms 60 which support the bladed cylinder 44 are mounted to swing 35 about the center of the shaft 62 there is no shifting or disturbance of the sprockets or trouble from tightening or loosening of the chains due simply to oscillation of the arms 60.**

40 Power means is provided for driving the feed roll 28 and also the bed roll 20 when the two rolls are in co-operative relation. Fixed to the shaft 140 of the feed roll 28 is a gear 142 with which the gear 144 fixed to the shaft 146 of the bed roll 20 is adapted to 45 mesh when the bed roll moves to the position shown in Fig. 4. It will be understood then that the bed roll is positively driven from the feed roll and in an opposite direction so that the bed roll and feed roll operate to feed 50 the work from front to rear of the machine when the work is first introduced, although as will be hereinafter described, the direction of feed may be changed at the will of the operator so that the whole of the work or any 55 given portion thereof may be fed back and forth repeatedly as often as is desired to secure repetition of the operations of the bladed cylinders. As will be made clear during the 60 further description of the driving means, the cylinders are driven independently of the feed rolls and constantly in the same directions while the feed rolls may have their directions of rotation reversed repeatedly to feed the work from front to rear and from rear 65 to front of the machine. Referring to Fig.

4 of the drawings it will be observed that during the feed of the work from front to rear of the machine the rear cylinder 42 assists in the feed of the work at the same time that it is operating upon the work in co-operation with the bed roll 20. During this time the front cylinder 44 is turning in a direction to operate very effectively upon the work which is being fed in a direction the reverse of that of rotation of this cylinder 44. Now, when the feed rolls 20, 28 are reversed in their direction of rotation, the cylinders 42, 44 continuing in the same directions as before, the front cylinder 44 becomes the cylinder which assists in feeding the work, while the rear cylinder 42 is assisted in its operation upon the work by the fact that the work is being moved in a direction opposite to that of rotation of this cylinder 42. It will thus be clear that there is provided an especially effective arrangement of the bladed cylinders in conjunction with the feeding means and that, while both cylinders continue to operate upon the work, first one and then the other becomes more efficient 90 because of the change in the direction of feed of the work. As will hereinafter be described, the feed rolls may be reversed by the operator at will, thus enabling him to secure repeated operation of the bladed cylinders and 95 of the rolls for heavy rolling upon any selected part of the work which, because of its condition, needs special treatment. In any case the whole piece of work will receive treatment even if it is passed only once by the 100 bladed cylinders which are so spaced that a part not operated upon by one bladed cylinder may be operated upon by the other. Hence, there is no necessity for introducing the work into the machine more than once. 105 In other words, the handling of the work by the operator is reduced to the minimum. This is in direct contrast to many of the old constructions in which the work has to be introduced at least twice, since only one part 110 at a time is operated upon by the machine, this being particularly true of present day fleshing and unhairing machines. A feature which adds considerably to the efficiency of the cylinders 42, 44 resides in the fact that 115 they are driven at a higher rate of speed than the feed rolls, and it is because of this that each feed roll in turn may assist in feeding the work in co-operation with the bed roll.

120 It will be recalled that the front cylinder 44 is driven from the rear cylinder by means including the sprocket chain 134 (Fig. 5) whereby there is provided means for driving the front cylinder at the same rate but in a direction reverse to that of the rear cylinder 42. The means for driving the rear cylinder according to the illustrated construction will 125 now be described. On the shaft 86 is a sleeve or bearing 200 (Fig. 7) on which is fitted a driving pulley 202 adapted to be driven by 130

a belt leading to a line shaft (not shown) or to any other desired source of power. Secured to sleeve 200 is a chain sprocket 204 around which passes a chain 206 (Figs. 7, 8 and 10) which drives a chain sprocket 208 carried fixedly by a shaft 210. As shown (Fig. 7), this shaft 210 is in alinement with the axis of the cylinder 42 and is rigidly secured to the cylinder as the immediate driving means for the same. It will be understood, then, that upon starting the driving pulley 202 in rotation the cylinders 42 and 44 begin to rotate and continue in rotation as long as power is supplied to the machine through the said pulley.

After a piece of work has been placed upon the bed roll 20 the latter is caused to move from the open work-receiving position of Fig. 3 into the work-operating position illustrated in Fig. 4, and at the same time the front cylinder 44 moves downwardly so as to co-operate with the bed roll 20 in setting operations upon the work. After the work has been operated upon to the desired extent, the bed roll and cylinder are caused to move in the reverse direction at the will of the operator, that is, into the open work-receiving position of Fig. 3. The means utilized in the illustrated machine for causing these movements of the bed roll and of the movable cylinder will now be described. Mounted fixedly on the shaft 210 is a chain sprocket 212 (Fig. 10) over which passes a sprocket chain 214 arranged to pass around an idler sprocket 216 and also over a sprocket 218 fixed to a pinion shaft 220, whereby shaft 220 is driven from shaft 210. Securely attached to the shaft 220 is a pinion 222 (Fig. 7) arranged to drive a clutch gear 224. When the operator depresses a treadle 226, provided for the purpose of controlling the in-and-out movements of the bed roll and front cylinder, it affects these movements by connections which comprise a lever 228 (Figs. 7 and 8) and a link connection 230 pivoted to the lever at one end and at its other end to the upper end of an arm 232 which is rigid with the treadle. As shown, the treadle 226 is pivoted upon a stub shaft 227, the latter being fixedly mounted in a bearing 229 secured to the base of the machine. Depression of the treadle results in swinging the lever 228 in the direction indicated by the arrow in Fig. 7 with the result that segment gears 234 and 236 which are constantly in mesh with each other co-operate to cause rotation of a vertical shaft 238 fixed to which is a cam lever 240. Carried by the end of the cam lever 240 is a cam block 242 adapted to engage alternately with notches 244 in a cam wheel 246, the notches being disposed 180° apart on the surface of the cam wheel. The cam wheel 246 is secured to the shaft 86, and the arrangement is such that a clutch to be described is held in operation for one half a revolution of the shaft 86, that is,

until the cam block 242 drops into the other notch which is brought around into co-operative position at the end of a half revolution of the shaft 86. On the lower end of the shaft 238 fixedly secured thereto is a shipper yoke 248, the forked end of which carries rollers for engagement in the usual manner in a groove in a cone 250 which puts into operation a clutch 252 to connect a shaft 254 to the gear 224. The shaft 254 has fixed thereto a chain sprocket 256 (Fig. 2) over which passes a chain 258 (Fig. 7) which also passes around an idler sprocket 260, loose on shaft 220 (Fig. 2), and a sprocket 262 (Fig. 8) to drive the shaft 86. It will be recalled that in the early part of the specification the driving connections between the shaft 86 and the bed roll 20 and the front cylinder 44 were described in detail, the said connections comprising two pairs of eccentrics 88, 100 on the shaft 86. When the treadle 226 is depressed it should be moved sufficiently to withdraw the cam block 242 from the notch 244 in the cam wheel 246. As soon as this has been accomplished the treadle should be released in order that the cam wheel 246 with its notches 244, may determine the amount of rotation of the shaft 86. At the same time that the block 242 is moved out of the notch 244 by depression of the treadle the cone 250 causes clutching of the shaft 254 to the gear 224 whereby the shaft 86 is caused to rotate, the cone 250 and the clutch 252 being held in operative position as long as the cam block 242 rides upon the surface of the cam wheel 246 and until it drops into the other notch at the end of one half of a revolution of the shaft 86, the block 242 being held against the surface of the cam wheel through the operation of a spring 263. When the shaft 86 makes one half a revolution it moves the eccentrics 88 and 100 (Figs. 3 and 4) to cause the bed roll 20 and the front cylinder 44 to move to open position (Fig. 3) or to work-operating position (Fig. 4) and then to rest in such positions until the treadle 226 is again depressed.

Means is provided in the illustrated machine for positively driving the feed roll 28, the said means comprising the shaft 210 which, through driving connections already described drives the shaft 220 to which is fixed a gear 270 (Figs. 2 and 9) which is arranged to mesh with a clutch gear 272 on a reversing clutch shaft 274. Fixed on the shaft 220 is a gear 276 which drives a clutch gear 278 through an intermediate gear 280, the latter being loosely mounted on a stub shaft 282. Mounted fixedly on the shaft 274 is a pinion 284 which drives a gear 286 fixed to a second stub shaft 288 which carries fixedly secured thereto a chain sprocket 290. Passing around the chain sprocket 290 is a chain 292 which extends to and drives a sprocket 294 fixed on the feed roll shaft 140. As before stated the feed roll shaft through a gear 142 is

arranged to drive the bed roll when the latter moves into operative position, the driving connection being established by the gear 144 on the bed roll shaft coming into meshing relation with the gear 142 on the feed roll shaft. Hence, the bed roll is driven through power means furnished by the drive of the feed roll, the two rolls moving in opposite directions at the same rate of speed to feed the work from front to rear of the machine and turning in the reverse directions again to feed the work from rear to front of the machine. This control of the feeding means is exercised by the operator in a manner to be described so that the whole of a piece of work or any given portion thereof may be fed forwardly and backwardly as often as is desired to secure thorough treatment by the cylinders and by the feed rolls themselves operating as rolling devices.

Referring to the means for reversing the direction of rotation of the feed roll and bed roll there is provided in the construction shown a manually controllable lever 300 at the front of the machine where it is easily accessible to the operator. As shown, it is mounted loosely on the stub shaft 227 (Figs. 9 and 10) and is connected by a link 302 to an arm 304 fixedly carried by a shaft 306 mounted in bearings 307 carried by the base of the machine. This shaft 306 is a shipper shaft which carries at its other end fixedly secured thereto a shipper yoke 308 arranged to be connected in the usual way, that is, by rollers and a groove to a double cone 310. This cone is movable in opposite directions to operate a clutch 312 and, alternatively, a clutch 314. When the clutch 312 is operated it connects the clutch gear 272 to drive the shaft 274 so that the work is fed from front to rear of the machine. When clutch 314 is operated by a reverse movement of the control lever 300, the clutch gear 278 is connected to drive the shaft 274 in the opposite direction so that the work is fed from rear to front of the machine. In the intermediate position of the double cone 310 the feed rolls are stationary. Hence, the bed roll 20 with its gear 144 may be moved into co-operative relation with respect to the feed roll 28 and the driving gear 142 thereof while the latter is stationary. It will be clear that the manually controllable lever 300 may be utilized to cause feeding of the work from front to rear of the machine or from rear to front or that the work may be held stationary for any desired length of time while the cylinders operate upon a certain portion of the work. Furthermore, after a given portion of the work has been operated upon as often as may be necessary to secure the desired results the whole piece of work may be passed continuously in one direction from front to rear of the machine to discharge the piece of work and to insure that no line of demarcation will be left upon

the surface of the work between parts which have received repeated operations and those receiving less treatment. The result is that the work as it comes from the machine is free of any lines or markings and has a clear even 70 color.

Having described my invention, what I claim as new and desire to secure by Letters Patent of the United States is:—

1. In a machine of the character described, feed rolls for supporting and feeding work, a pair of cylinders, means for causing simultaneous operation of the cylinders on the work at a predetermined pressure, and means under the control of the operator for reversing the direction of feed of the feed rolls while the cylinders continue operating as before, whereby portions of the work may be fed in opposite directions and operated upon repeatedly without withdrawing the work from and re-introducing it into the machine. 75

2. In a machine of the character described, a bed roll, a feed roll co-operating therewith for feeding work, two cylinders arranged to co-operate with the bed roll in operations on the work, means for moving the bed roll and one of the cylinders between work receiving and work operating positions, means for driving the cylinders in opposite directions and for causing them to operate simultaneously on the work, and means under the control of the operator for reversing at any time the feeding movement of the two rolls while the cylinders continue operating as before so that the work may be fed in opposite directions and the whole or selected portions thereof operated upon repeatedly after the work has once been introduced into the machine. 90

3. In a machine of the character described, feed rolls for supporting and feeding work, a pair of arms pivotally mounted to move one feed roll into co-operative relation to the other, the pivotal mounting of the arms being in the plane defined by the axes of the co-operating rolls, thus providing such support for the rolls as to make possible heavy rolling of the work during feeding thereof, a cylinder for operating on the work, and means under the control of the operator for reversing the direction of feed of the feed rolls while the cylinder continues operating as before, whereby portions of the work may be fed in opposite directions and operated upon repeatedly without withdrawing the work 105 from and reintroducing it into the machine. 110

4. In a machine of the character described, a bed roll, a feed roll co-operating therewith for feeding work, power means for driving both rolls to feed and to roll the work, two cylinders, one located on each side of the feed roll for operating on the work in co-operation with the bed roll, means for moving the bed roll and one of the cylinders between work receiving and work operating posi- 120 125

5 tions, means for driving the cylinders in opposite directions and for causing them to operate simultaneously on the work, and means under the control of the operator for reversing the feeding movements of the two rolls while the cylinders continue in the same directions as before whereby the cylinder in advance in the direction of feed of the work aids in feeding the work while the other cylinder operates on work passing in a direction opposite to that of its movement of rotation thus securing maximum operating results from the cylinders irrespective of the direction of feed of the work.

10 5. In a machine of the character described, a feed roll, a cylinder for operating on work, means for mounting the feed roll and the cylinder for rotation in the frame of the machine, a bed roll mounted for movement toward and away from operative position with respect to the feed roll and cylinder, a second work operating cylinder, power means for moving the last mentioned cylinder into co-operative relation with the bed roll, means for driving the work operating cylinders simultaneously and in opposite directions, and means for causing at the will of the operator feed movements of the work first in one direction and then in another so that the work or any given portion thereof may be operated upon repeatedly after the work has been once introduced into the machine.

15 6. In a machine of the character described, a feed roll, means for mounting the feed roll in the frame of the machine, a bed roll for supporting work, a support for the bed roll movable to position the bed roll in work receiving and in work feeding positions, a cylinder for operating on work supported on the bed roll, a second cylinder for operating on the work on the bed roll at the other side of the feed roll, power means for moving the second cylinder into and out of co-operative relation with respect to the bed roll, power means for rotating the cylinders in opposite directions and for causing them to operate simultaneously upon the work, and means for causing the feed roll and the bed roll to change at any time the direction of their rotation whereby the work may be fed in opposite directions and operated upon repeatedly at the will of the operator.

20 7. In a machine of the character described, a feed roll, a cylinder for operating on work, means for mounting the feed roll and the cylinder for rotation on the frame of the machine, a bed roll mounted for movement toward and away from operative position with respect to the feed roll and cylinder, said feed roll and bed roll co-operating as feed rolls for the work, a second work operating cylinder, power means for moving the last mentioned cylinder into co-operative relation with the bed roll, means for driving the work operating cylinders in opposite directions

25 with respect to each other, and at higher rates of speed than the feed rolls are driven, and means for causing at the will of the operator feed movements of the work first in one direction and then in another so that the work or any given portion thereof may be operated upon repeatedly after the work has been once introduced into the machine.

30 8. In a machine of the character described, a feed roll, means for mounting the feed roll in the frame of the machine, a bed roll for supporting work, a support for the bed roll movable to position the bed roll in work receiving and in work feeding positions, said feed roll being adjustable to a definite spaced relation with respect to the bed roll, heavy spring means for yieldingly maintaining the feed roll in adjusted position, a cylinder for operating on work supported on the bed roll, a second cylinder for operating on the work at the other side of the feed roll, power means for moving the second cylinder into and out of co-operative relation with respect to the bed roll, power means for rotating the cylinders, the feed roll and the bed roll for causing operations on the work and heavy rolling thereof simultaneously with the feeding of the work, and means for causing at the will of the operator the feed roll and the bed roll to change the direction of their rotation whereby the work may be fed in opposite directions and operated upon repeatedly after it has been once introduced into the machine.

35 9. In a machine for working on hides, skins, and leather, a feed roll mounted for rotation in the frame of the machine, a bed roll for supporting work and for co-operating with the feed roll in feeding the work, a support for the bed roll directly under the feed roll, means for moving the bed roll alternately to inoperative work receiving position and to work clamping and feeding position directly in line between the feed roll and said support, whereby heavy rolling of the work takes place simultaneously with the feeding thereof, and work operating cylinders located one on each side of the feed roll for co-operation with the bed roll in operating on the work.

40 10. In a machine for working on hides, skins and leather, a feed roll mounted for rotation in bearings in the frame of the machine, a bed roll movable alternately from work receiving position to work feeding position in co-operation with the feed roll, a work operating cylinder located at one side of the feed roll for co-operation with the bed roll in operating on the work, a work operating cylinder movable into and out of co-operative relation to the bed roll, a shaft supported by the frame of the machine in parallel relation to the bed roll and the movable cylinder, eccentrics on the shaft, and connections from the eccentrics to the bed roll and to the movable cylinder for moving the bed

roll and cylinder alternately into co-operative relation and to a widely spaced work receiving relation with respect to each other.

11. In a machine for working on hides, skins and leather, a feed roll mounted for rotation in the frame of the machine, a bed roll movable alternately into and out of co-operative work clamping relation with the feed roll, means for providing an unyield-

10 ing support for the bed roll in the plane defined by the axes of the rolls when they are in co-operative relation to each other, power means for driving both the bed roll and the feed roll whereby the work may be subjected 15 to a heavy rolling operation, and a work operating cylinder arranged for co-operation with the bed roll in operating on the work.

12. In a machine for working on hides, skins and leather, a feed roll mounted for rotation in the frame of the machine, a bed roll movable from work receiving position into co-operative relation with the feed roll in feeding the work, work operating cylinders one on each side of the feed roll for co-operation with the bed roll in operating on the work, means for adjusting the work cylinders and the feed roll toward and from the bed roll, and means for mounting the cylinders and the feed roll to yield in accordance 20 with variations in the thickness of the work.

13. In a machine for working on hides, skins and leather, feed rolls for feeding work, one of the feed rolls serving also as a bed roll for supporting the work during operations thereon, a pair of cylinders for operating at predetermined pressures on the work in co-operation with the bed roll, means for driving the cylinders for rotation in opposite directions, and means for reversing the 25 feed of the feed rolls while the cylinders continue their rotation in the same directions as before whereby one of the cylinders assists in the feeding of the work during direct feeding thereof and the other during reverse feeding thereof.

14. In a machine of the character described, a bed roll, a feed roll for co-operation with the bed roll in feeding work, a cylinder having blades for operating on the work supported on the bed roll, means having a common element for moving the cylinder and the bed roll one in a downward direction and the other in an upward direction into work receiving position, the said means being operative also to move the bed roll and the cylinder in reverse directions into co-operative relation with respect to work supported on the bed roll, and means for mounting the bed roll and the movable cylinder for operation by the 30 moving means, the construction and arrangement of the moving means being such that movement of the bed roll and cylinder in opposite directions reduces the strain and jar on the machine parts.

15. In a machine of the character described,

a feed roll, a bed roll movable from and toward the feed roll, a bladed cylinder movable toward and from the bed roll, a shaft, an eccentric on the shaft for moving the bed roll, and a second eccentric on the shaft for moving the bladed cylinder, the eccentrics being in reverse relation thereby reducing to a minimum the strains tending to bend the shaft.

16. In a machine of the character described, means comprising a bed roll for supporting and feeding sheet leather material, a pair of cylinders for operating on the sheet material, one of the cylinders being stationary in space and the other movable toward and from the bed roll, means for driving the cylinders for rotation in opposite directions, and means for reversing at will the feed of the sheet material, whereby the sheet material or any given portion thereof may be operated upon 30 repeatedly to obtain the results desired by the operator.

17. In a machine of the character described, means comprising a bed roll for supporting and feeding leather material, a cylinder for operating at a predetermined pressure on the leather material supported by the bed roll, means for driving the cylinder at a higher speed than that of the feed of the sheet material, and means for reversing at will the 40 direction of feed of the leather sheet material while the cylinder continues to rotate in the same direction as before, whereby the leather material may be subjected to repeated operations upon the whole or any given part 45 thereof.

18. In a machine for working on hides, skins and leather, a feed roll mounted for rotation in the frame of the machine, a bed roll movable from work receiving position into cooperative relation with the feed roll to feed the work, work operating cylinders one on each side of the feed roll for co-operation with the bed roll in operating on the work, and means for moving one of the cylinders 50 into co-operation with the bed roll after the latter has moved into co-operative relation with respect to the other work operating cylinder.

19. In a machine of the character described, a feed roll, means comprising a movable bed roll for supporting and feeding hides, skins or other leather material, a cylinder for operating on the leather material supported by the bed roll, means for operating the cylinder at a predetermined pressure with respect to the leather material supported by the bed roll, and power means for moving the cylinder into the desired co-operative relation with respect to the bed roll after the latter has moved into cooperative relation 60 with respect to the feed roll.

20. In a machine for working on hides, skins and leather, feed rolls for feeding work, one of the feed rolls serving also as a bed roll

for supporting the work during operations thereon, a pair of cylinders, the cylinders being located one on each side of the plane passing through the feed roll and the bed roll, 5 means for driving the cylinders in opposite directions and at a higher speed than that of the feed rolls, means for causing the cylinders to operate at predetermined pressures with respect to the work supported by the bed roll, and means for reversing the direction of 10 rotation of the feed rolls while the cylinders continue rotation in the same directions as before whereby first one cylinder and then the other operates to assist in feeding the 15 work while operating thereon.

In testimony whereof I have signed my name to this specification.

JOHN W. O'DONNELL.
